UNITED STATES PATENT OFFICE

JAMES COMLY, OF PHILADELPHIA, PENNSYLVANIA.

DESIGN FOR BOXES.

Specification forming part of Design No. **7,568**, dated July 21, 1874; application filed June 8, 1874.
[Term of Patent 7 years.]

To all whom it may concern:

Be it known that I, JAMES COMLY, of the city and county of Philadelphia and State of Pennsylvania, have invented a Design for Boxes, of which the following is a specification:

The nature of my design is fully represented in the accompanying photographic illustration to which reference is made.

The form of the box is that of a building, in which *a* represents the front thereof, and *b* *b* the windows arranged in three rows. *c* is an arched doorway, and *d* an arched window above the door. The windows of the middle row have balconies *c'*. There is a central peak, *d'*, a small tower, *e*, at one corner, and a large tower, *f*, at the other corner. The tower *f* has pinnacles *g* at the corners of its top and windows *h* in its sides. The sides *k* of

building have four rows of windows, *l*, but the corresponding side of the tower has three windows. A door, *m*, is located on the first floor aside of the tower. A peak, *n*, is at the top of the side *k*.

I claim as my invention—

The design for a box in the form of a building, having its front *a* formed with three rows of windows, *b*, the arched doorway *c*, arched window *d*, and central peak *d'*, the sides *k* with four rows of windows, *l*, door *m*, and peak *n*, and the front corners with towers *e*/*f*, one tower, *f*, having pinnacles *g* and windows *h*, all as shown and described.

JAMES COMLY.
